UNITED STATES PATENT OFFICE.

WILLIAM A. FLANAGAN, OF RIPON, CALIFORNIA, ASSIGNOR OF ONE-HALF TO JOHN W. GARRISON, OF RIPON, CALIFORNIA, AND ONE-HALF TO WESTERN WHEELED SCRAPER COMPANY, OF AURORA, ILLINOIS, A CORPORATION OF ILLINOIS.

BALLAST CAR.

Application filed May 11, 1925. Serial No. 29,517.

This invention relates to improvements in ballast or dump cars of the stationary body, bottom-discharge type such as are used on railroads for dumping rock and gravel 5 ballast onto the road bed.

One of the objects of my invention is to provide a car of this general character whose discharge gates may be controlled either by hand or by power, the use of either means 10 being optional. The power I use is air, and the air actuated mechanism is of such a character that the air may be controlled and the mechanism operated by the same kind of apparatus used in applying air 15 brakes, and which may be controlled from the engine to which one or any number of the cars are attached.

In this manner the dumping of an entire train load of cars may be done at a 20 single operation, by the engineer of the train, and without the need of other helpers.

A further object of the invention is to provide a car of this type having a number 25 of discharge gates, connected to a single power operating means in such a manner that all or any number of the gates may be operated simultaneously. This operation may be carried out by hand also.

By means of this arrangement only those 30 gates on one side or the other of the car may be operated, as may be necessary, or even only one gate on such side may be opened, if it is desired to only dump a portion of the carload. This enables good control 35 of dumping operations to be had and allows the contents of the cars to be dumped where most needed, without subsequent transferring of part of the load from one side of the track to the other being necessary.

Still another object is to arrange the gate 40 control means in such a manner that only a slight initial power or hand movement is necessary to cause the gates to be unlocked, after which the weight of the load 45 itself will cause the gates to fully open. This conserves power and makes for easy and quick operation.

The gates are so arranged that when 50 opened they form aprons or chutes for the material, and cause the latter to be discharged clear of the tracks.

These objects I accomplish by means of 55 such structure and relative arrangement of

parts as will fully appear by a perusal of the following specification and claims. 55

In the drawings similar characters of reference indicate corresponding parts in the several views:

Fig. 1 is a side elevation of the car.

Figs. 2 and 3 are cross-sections on the 60 line 2—2 of Fig. 1, showing the gates in locked and fully opened positions, respectively.

Fig. 4 is a fragmentary cross section on the line 4—4 of Fig. 1, showing the gates 65 as initially unlocked by the operation of the power means.

Fig. 5 is a fragmentary cross section on the line 5—5 of Fig. 1 showing a shaft-clutch operating lever. 70

Fig. 6 is a fragmentary top plan view 75 of the car frame showing a hand control and clutch operating mechanism for one of the main gate controlling shafts.

Fig. 7 is a fragmentary top plan view enlarged of the hand control mechanism.

Fig. 8 is a cross section on the line 8—8 of Fig. 7.

Fig. 9 is a sectional elevation of a shaft 80 connection or clutch means.

Referring now more particularly to the characters of reference on the drawings, the frame of the car includes a longitudinal center beam 1 and side beams 2. The latter preferably terminate short of the ends 85 of the center beam, and have at their ends transverse beams 3, which connect the beams 1 and 2 together to form a rigid structure, and which support the wheel trucks 4 of common character. The usual coupling and air hose connection means (not shown) are mounted at the outer ends of the frame beyond the trucks, as is customary. The body 5 of the car projects upwardly from and is supported by the frame in any suitable manner, and is divided into two longitudinal compartments by a central transverse partition 6. The sides of the body a certain 90 distance from the top converge to a longitudinal and centrally located apex at the bottom, and the opposite ends of the compartments similarly slope down to meet said longitudinal apex at points inwardly of the plane of the wheel trucks. 95

The greater portion of both sloping sides 100 of the compartments are in the form of gates 105

7 hinged along the longitudinal apex of the body as at 8. From the ends of the gates transverse side plates 9 project outwardly from the body, said plates having flanges 10 along their edges extending outwardly from the central hinge at a downward slope, and serving as rests for the gates when the latter are fully opened.

The area of the plates relative to the gates 10 and their positions relative to the body openings of said gates is such that the material being discharged from the body is completely confined between said plates, and cannot spread laterally until entirely clear of the car. The width of the gates is such that when fully opened and resting on the flanges 10 their outer edges are then outwardly of the plane of the wheel trucks, as shown by Figs. 2 and 3.

20 The frame of the car also includes transverse beams 11 disposed below the beams 1 and 2 and between the trucks 4. These beams are supported at their ends by rigid hanger members 12 depending from the beams 2.

These transverse beams 11 form end supports for longitudinally disposed and transversely spaced shaft members 13. Although these shafts are broken intermediate their 30 ends and are connected by clutch means, as hereinafter seen, each shaft member when thus connected forms a rigid and practically unitary structure, and will so be considered at present.

35 Rigidly fixed on each shaft, and projecting upwardly therefrom are arms 14, at least one for each gate and centrally located relative to the length of the gates. The upper ends of the arms are pivoted onto links 15 whose upper ends in turn are pivotally connected to the gates. These members form knuckle joint connections between the shaft and the gates, and are so arranged that when the gates are closed the arms and the links 40 are past a dead center position, as shown in Fig. 2, and prevent the gates from opening until said linkage members are moved past dead center in the opposite direction.

The shafts 13 have each two pairs of longitudinally spaced and transversely aligned cranks 16 therein, between each pair of which cranks rigid arms 17 extend, the cranks on each shaft being disposed at the same angle so that the arms are parallel to 55 each other on the respective shafts.

The cranks on the different shafts are so disposed that when the arms are moved longitudinally of themselves or transversely of the car in one direction, the shafts 13 will be 60 turned in opposite directions simultaneously, to simultaneously operate the gate connecting linkage in a manner to cause the gates to be opened or closed, as the case may be.

65 The power mechanism for thus moving the shafts is located between the adjacent

and centrally located side plates 9 and is constructed as follows:

Mounted between the arms 17 in horizontal and transverse alinement relative to the car is an air cylinder 18, having a piston 19, piston rod 20, and spring 21 acting to normally hold the piston at the rear end of the cylinder (see Figs. 2 and 4). This mechanism may be identical with that used to apply air brakes and consequently has included therewith the reservoir 22 and triple valve 23, such as are commonly used in connection with standard air brake apparatus. By the addition of the necessary piping and other standard features (not shown), my air mechanism may therefore be operated in the same manner as the brakes, that is from the engine or from each car individually.

Flexibly connected to the outer end of the piston rod is a link 24 to the outer end of which is pivoted an arm 25 having a longitudinal slot 26 adjacent its outer end. The pivotal connection between the link and the arm is in the form of a pin 27 which extends longitudinally of the car or transversely of the arms 17 and across the same. Said pin at times, as hereinafter shown, is arranged to seat in recesses 28 cut in the upper edges of the arms 17.

Normally however (when the piston is retracted in the cylinder and the gates are closed) this pin is ahead of the recesses and is then positioned to enter guides 29 extending away from the cylinder on an upward slope and pivoted onto the adjacent plates 9. Stop means 30 is employed for preventing downward movement of the guides without interfering with their upward movement about their pivot.

100 Fixed on the shaft 13 toward which the piston rod 20 faces is a crank 31 whose crank pin 32 passes through the slot 26. This crank is so disposed that when the piston rod is contracted and the gates closed, said crank lies above the shaft at an outward slant such that its pin 32 is then at the outer end of the slot in the member 25, as shown in Fig. 2. The crank 31 is also so disposed relative to the adjacent crank 16, that when said crank 32 rotates by the advancing movement of the piston rod outwardly of the cylinder, the arms 17 will be moved in a direction opposite to the said piston rod.

115 In operation when the parts are in their normal or neutral position, as in Fig. 2, and it is desired to open the gates, air is applied to the cylinder 18 to cause the piston to be advanced. The piston travels without resistance except for that offered by the spring 21, until the inner or rear end of the slot 26 120 engages the crank pin 32. This causes an initial rotation to be imparted to said crank and to the shafts 13, as shown in Fig. 4. This rotation, imparted to both shafts 13 through the connecting arms 17, causes the 125 130

linkage connected with the gates to be unlocked, and the weight of the material in the car will then bear on the gages and lower them independently of any air pressure.

5 During this movement of the parts the pin 27 is engaged by the guides 29, so that it is raised from the arms 17 and cannot enter the recesses therein.

As soon as the initial rotative effect has 10 been imparted to the shafts as above stated, the air may be released, and the piston rod will return to its normal or retracted position in the cylinder by reason of the spring 21.

15 The rod 27 will then leave the guides, and as the arms 17 move back with the rotation of the shafts with the full opening movement of the gates, the recesses 28 in said arms will align vertically with the pin 27. The latter will then drop into said recesses as shown in Fig. 3, owing to the link 24 on which said pin is mounted being freely hung.

Now when it is desired to close the gates 25 the air is again applied to the cylinder, and the arms will be moved in a direction opposite to their gate opening movement, due to the engagement of the pin 27 therewith, until, when the full stroke of the piston rod has been had, the gates will be restored to a fully closed position and the linkage connections moved past a dead-center position as shown in Fig. 2.

The pin 27 is then still engaged with the 35 recesses 28, and is beyond the lower ends of the guides 29. Since, however, said guides are free to lift, with the release of the air and the return of the piston rod and pin to their normal positions, said pin 40 merely passes under and raises the guides until it clears the same and resumes its normal setting relative thereto. It is then ready to again enter the guides when another door opening operation is to be carried out.

The opening and closing operations of the gates is therefore controlled in a very simple manner merely by two air applying and releasing operations in connection with 50 an ordinary air brake cylinder or similar type of apparatus.

Owing to the gates being pivoted in common along the bottom of the body, when said gates are open, all material in the body 55 must positively leave the same, as no pockets are formed which would necessitate the use of a shovel or other means to aid in the discharging of the contents of the car.

Besides the end supports 11 for the shafts 60 13, intermediate supports 33 are provided which extend thereto from the central beam 1, these supports being located adjacent the arms 14 so as to prevent the same from being deflected, when under load.

65 If the shafts 13 were rigid throughout,

all gates would per-force be opened when the air was applied. I have therefore provided means controllable at will for enabling any of the gates to be maintained closed if desired.

To accomplish this I split each shaft 13 70 between each of the arms 14 and the adjacent crank 16, and place independent hand operated clutch means therebetween. This clutch structure may be of any suitable 75 type. In the present instance I have shown the adjacent ends of each shaft 13 as having polygonal sided portions, with a sleeve 34 slidable over such portions and free to clear one of the shaft ends. It will therefore be seen that when the sleeve is over both shaft sections, the shaft will then turn as one. If, however, the sleeve is moved clear of a section, that portion of the shaft to which the corresponding arm 14 is connected will have no movement imparted thereto with the rotation of the other portion of the shaft, and the corresponding gate will consequently remain closed.

To facilitate control of the sleeves, I provide an operating lever 35 for each one, extending thence toward the side of the car, the outer end of said lever being slidable in a guide 36 mounted on a longitudinal support 37 which extends between the lower 95 ends of the hangers 12.

In addition to the power operating means I provide hand control means for rotating the shafts 13. Such means, for each end 100 of each shaft, comprises a bevel gear 38 on the outer end of the shaft meshing with a bevel pinion 39 on a shaft 40. This shaft extends transversely to the corresponding side of the car and carries a hand wheel 41 on its outer end.

To normally prevent rotation of the shaft 40 in that direction which would allow the corresponding gate to open, I provide a shrouded ratchet wheel 42 on the shaft 40. This wheel is engaged by a pawl 43 mounted on a bracket 44 in which the shaft 40 is slidably mounted for limited longitudinal movement. The pawl is fixed against longitudinal displacement and when engaged with the ratchet is disposed between the shrouds thereof. The shaft is then held against longitudinal movement, the position of the shaft being then such that the pinion and gear are in mesh. This is the position occupied by the parts when it is desired to operate any gate by hand. In this case the corresponding clutch sleeve 34 is disengaged to enable that portion of the shaft 13 to which the hand wheel and corresponding gate control arm 14 are connected to turn 120 without imparting any movement to the air operated apparatus.

If the gates are to be operated by air, however, the pawl is lifted from the ratchet 125 so as to clear the shrouds and the shaft 40 130

is drawn outwardly so as to disengage the pinion and gear. The pawl is then allowed to drop back on the outside of the ratchet wheel, in which position said pawl acts as a stop preventing retractive movement of the shaft 40.

In the event that a separate air control valve on the engine, and an individual air line system for my air operated means, is not available or desired, a hand controlled branch line, tapping the main air brake line at each end of the car, may be employed. In this case the air operated mechanism may be controlled by the ordinary engineer's 15 brake valve.

While I have specifically shown and described this structure as being a railroad car, at the same time it could be mounted on a motor truck chassis. In this case an air 20 compressor and a reservoir would be provided on the truck to be operated by the engine thereof, so as to provide the necessary air power for operating my device.

From the foregoing description it will be 25 readily seen that I have produced such a device as substantially fulfills the objects of the invention as set forth herein.

While this specification sets forth in detail the present and preferred construction 30 of the device, still in practice such deviations from such detail may be resorted to as do not form a departure from the spirit of the invention, as defined by the appended claims.

Having thus described my invention what 35 I claim as new and useful and desire to secure by Letters Patent is:

1. A ballast car including a body, downwardly opening gates hinged along the bottom of the body, a power operated mechanism common to all the gates for operating the same, and individual hand controlled means for each gate in addition to the power mechanism, for operating the gates.

2. A ballast car including a body, downwardly opening gates hinged along the bottom of the body, a power operated mechanism common to all the gates for operating the same, individual hand controlled means for each gate for operating the same, means whereby when the hand controlled means is in operation the power mechanism will not be disturbed, and means whereby when the power mechanism is in operation the hand means will not be disturbed.

3. A ballast car including a body, a downwardly opening gate hinged along the bottom of the body, a shaft member disposed longitudinally of the car under the gates, linkage between the shaft and gate arranged to cause the gate to be opened and closed with the rotation of the shaft in opposite directions, power means applied to the shaft for thus rotating the same, hand means for independently rotating the shaft, and means for disconnecting the shaft from

the power means when the hand means is in use.

4. A ballast car including a body, a downwardly opening gate hinged along the bottom of the body, a shaft member disposed 70 longitudinally of the car under the gates, linkage between the shaft and gate arranged to cause the gate to be opened and closed with the rotation of the shaft in opposite directions, power means applied to the shaft 75 for thus rotating the same, and means for disconnecting the shaft adjacent the linkage from driving relation with the power means, whereby said linkage will not then be moved with the operation of the power means. 80

5. A ballast car including a body, a downwardly opening gate hinged along the bottom of the body, a shaft member disposed longitudinally of the car under the gates, linkage between the shaft and gate arranged 85 to cause the gate to be opened and closed with the rotation of the shaft in opposite directions, power means applied to the shaft on one side of the linkage for thus rotating the shaft, hand operated means applied to 90 the shaft on the opposite side of the linkage for likewise rotating the shaft, and hand controlled clutch means in the shaft between the power means and the linkage.

6. A ballast car including a body, a downwardly opening gate hinged along the bottom of the body, a shaft member disposed 95 longitudinally of the car under the gates, linkage between the shaft and gate arranged to cause the gate to be opened and closed 100 with the rotation of the shaft in opposite directions, power means applied to the shaft on one side of the linkage for thus rotating the shaft, hand operated means applied to the shaft on the opposite side of the linkage 105 for likewise rotating the shaft, hand controlled clutch means in the shaft between the power means and the linkage, and independent means for disconnecting the hand operated means from driving relation with the 110 corresponding portion of the shaft.

7. A ballast car including a body, a downwardly opening gate hinged along the bottom of the body, a shaft member disposed 115 longitudinally of the car under the gates, linkage between the shaft and gate arranged to cause the gate to be opened and closed with the rotation of the shaft in opposite directions, power operated means for thus 120 rotating the shaft, said means including a rod moved longitudinally upon the application of the power, means whereby a movement of said rod in one direction will cause the shaft to be rotated in one direction, and means whereby a recurring movement of 125 said rod in the same direction will cause the shaft to be rotated in the opposite direction.

8. A ballast car including a body, a downwardly opening gate hinged along the bottom of the body, a shaft member disposed 130

longitudinally of the car under the gates, linkage between the shaft and gate arranged to cause the gate to be opened and closed with the rotation of the shaft in opposite directions, power operated means for thus rotating the shaft, said means including a rod moved longitudinally upon the application of the power, means whereby a movement of said rod in one direction will cause the shaft to be rotated in one direction, means acting automatically to retract the rod to its normal position when the power application is discontinued, and means whereby a further power application on the rod to move it in the same direction as with the first power application will cause the shaft to be rotated in the opposite direction.

9. A ballast car including a body, a downwardly opening gate mounted thereon, a shaft disposed longitudinally of the car mounted under the gate, an arm fixed on and projecting upwardly from the shaft, a link pivotally connected to the upper end of the 25 arm and to the gate, said link and arm being so arranged that when moved past a dead center position in one position they will be locked against movement, the gate being then closed; and power means for 30 rotating said shaft sufficiently to cause said arm and link to be moved past dead center in the opposite direction, whereby a load on the gate will then cause the same to be opened regardless of a continued operation 35 of the power means.

10. A ballast car including a body, downwardly opening gates on opposite sides of the same, shafts disposed longitudinally of the car mounted under the gates, connections 40 between the shafts and gates arranged to cause the gates to be opened and closed with a rotation of the shafts in opposite directions, cranks on the shafts, an arm extending between the cranks, a power means 45 including a horizontal disposed rod extending lengthwise of and adjacent said arm, said rod being arranged for power movement lengthwise of itself, toward one of the shafts, a crank on said shaft, a connection 50 between said rod and the last named crank, said different cranks being so arranged that when the gates are closed and the last named crank is initially moved by a movement of the rod the arm will move in 55 the opposite direction, means whereby when said initial turning movement is imparted to the crank the doors will then automatically open to their lowest limit, means for enabling said rod to return to its normal position, and means whereby the rod will then 60 be engaged in driving relation with the arm, whereby upon a further application of power on the rod the arm and rod will move together and in the same direction to reverse 65 the direction of rotation of the shafts.

11. A ballast car including a body, downwardly opening gates on opposite sides of the same, shafts disposed longitudinally of the car mounted under the gates, connections between the shafts and gates arranged 70 to cause the gates to be opened and closed with a rotation of the shafts in opposite directions, cranks on the shafts, an arm extending between the cranks, a power means including a horizontal disposed rod extending 75 lengthwise of and adjacent said arm, said rod being arranged for power movement lengthwise of itself, toward one of the shafts, a crank on said shaft, a link connected to the rod, an arm connected to the 80 link and having a slot through which the pin of the last named crank passes; a pin forming the pivot of the link and arm extending transversely across the other arm, 85 said other arm having a recess in its upper arm to receive the pin, means preventing the seating of the pin in the recess when the last named crank is engaged by the slotted arm to cause the shafts to turn in a door opening direction; said cranks being 90 so arranged that the arm extending between the shafts then moves in a direction opposite to that of the rod, and means whereby after a door opening rotation of the shafts 95 has taken place the rod may return to its original position without imparting movement to the shafts; the pin and recess being then vertically alined so that the pin may seat therein; whereby upon another application of power to the rod said recessed arm 100 will be moved by the action of the rod and in the same direction.

12. A ballast car including a body, a downwardly opening gate hinged along the bottom of the body, and power means for 105 opening and closing the gate, said means including a member moved upon the application of the power, means controlled by the movement of said member in one direction for causing the gate to be opened, and means 110 causing the gate to be closed with a recurring movement of said member in the same direction.

13. A ballast car including a body, a downwardly opening gate hinged along the bottom of the body, and power means for 115 opening and closing the gate, said means including a member moved upon the application of the power, means controlled by the movement of said member in one direction from a neutral position for causing the gate to be opened, means then acting automatically to restore said member to its neutral position, and means causing the gate to be 120 closed with a recurring movement of the member in the same direction.

In testimony whereof I affix my signature.

WILLIAM A. FLANAGAN.
